CLAIM

I claim the ornamental design for a two-card sleeve apparatus, as shown and described.

DESCRIPTION

FIG. 1 is a top, isometric view of an embodiment of a two-card sleeve apparatus, showing my new design;
 FIG. 2 is a front elevational view thereof;
 FIG. 3 is a back elevational view thereof;
 FIG. 4 is a left side elevational view thereof;
 FIG. 5 is a right side elevational view thereof;
 FIG. 6 is a bottom plan view thereof;
 FIG. 7 is a top plan view thereof;
 FIG. 8 is a cross-sectional view taken on line **8-8** of FIG. 1;
 FIG. 9 is a top, isometric view of a second embodiment of the two-card sleeve apparatus;
 FIG. 10 is a front elevational view thereof;
 FIG. 11 is a back elevational view thereof;
 FIG. 12 is a left side elevational view thereof;
 FIG. 13 is a right side elevational view thereof;
 FIG. 14 is a bottom plan view thereof;
 FIG. 15 is a top plan view thereof; and,
 FIG. 16 is a cross-sectional view taken on line **1-16** of FIG. 9.
